LIQUID TRANSFERRING APPARATUS

Roy S. McKeever, Tulsa, Okla., assignor, by
mesne assignments, to The Parkersburg Rig &
Reel Company, Parkersburg, W. Va., a cor-
poration of West Virginia

Application January 27, 1938, Serial No. 187,278

11 Claims. (Cl. 183—2.7)

This invention relates to improvements in means for transferring liquids and more especially to means for passing liquids from oil and gas separator to stock tanks or the like.

5 One of the objects of the invention is to provide novel means for transferring oil from a separator and delivering it to a stock tank or the like, which may in some instances be at a higher elevation than the separator.

10 Another object is to furnish delivery means which will eliminate the necessity of elevating the separator on a tower or elevated platform where the point of delivery is at a higher elevation than the separator.

15 A further object is to supply delivery means which will allow the lowering of pressure on the separator to atmospheric or subatmospheric and yet permit the delivery of the oil from the separator to the point of storage, even though the latter be at a higher elevation than the separator.

20 Another object is to provide delivery means which includes a tank or chamber that may be furnished as a unitary part of a separator or form a base for a separator.

25 A still further object is to supply delivery means including elements for measuring or metering the oil as it is delivered so that the operator can ascertain at any time just how much oil has been delivered from the separator.

30 Another object is to provide delivery systems employing three-way diaphragm valves so as to reduce the number of valves required in such a system.

35 With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is an elevation partly in vertical section of an oil and gas separator provided with my improvements; some features of the improvements being shown in vertical section.

40 Fig. 2 is a side elevation partly in vertical section and partly broken away of one of the motor or diaphragm valves forming part of the equipment.

45 Fig. 3 is a similar view of the float-operated pilot valve with its cover plate removed.

Fig. 4 is an end elevation of the structure shown in Fig. 3.

50 Referring to the drawings, 10 designates a con-

ventional oil and gas separator associated with a measuring or transferring chamber 11. In the embodiment of the invention illustrated the chamber or tank 11 forms the base of the oil and gas separator, and is segregated from the separating chamber by a partition 12 forming the bottom of one chamber and the top of the other. 5 13 designates the separator inlet and 14, the gas outlet which may be controlled by a fluid pressure-operated valve 15.

10 The oil outlet of the separator is connected by a conduit 16 to the chamber 11 so that oil discharged from the lower end of the separator will be passed through the chamber 11 before being conveyed by the pipe 17 to a storage tank or the like which may, if necessary, be arranged at a higher elevation than the separator.

15 A three-way valve 18, hereinafter described in detail, is interposed in the pipe 16 for alternately placing the tank 10 in communication with the pipe 17 and chamber 11.

20 Another three-way valve 19 of the same type is interposed in a conduit 20, 21 and is adapted to alternately open and close communication between the upper ends of the two tanks.

25 A by-pass pipe 22 having a hand-operated valve 23 connects portions of the pipes 20, 21 to place the upper portions of the tanks in direct communication when desired.

30 The valves 18 and 19 are controlled by fluid pressure which may be derived from an outside source through the pipe 24 or from an inside source through a tube 25 leading from the top portion of the separator. The pipe 24 is connected by a branch 26 to the valve 19 and the branch is provided with a hand-controlled valve 27. When that valve is open and the valve 19 is in a certain position, pressure fluid can flow through 24, 26 and 21 into the top portion of the auxiliary tank 11 for the purpose of forcing oil from that tank through the pipe 17.

35 If on the other hand the valve 27 is closed and the valve 19 is in the same position, and the valve 23 is open, pressure fluid from the top portion of the separator chamber 10 can flow through the pipe 22 and force oil from the tank 11.

40 A tube 28 having a hand-controlled valve 31 interposed therein, connects the branch 26 to the condensate chamber 30. The tube 25 having a hand-controlled valve 29 places the condensate chamber in communication with the upper end of the separator chamber 10. If either of the hand-controlled valves 29 or 31 is closed and the other opened, pressure fluid will flow to the condensate chamber. The pressure fluid flows from 45 50 55

the latter to a pressure gauge 32 and then through a tube 33 and reducing regulator 34* to a pilot valve 34, which will be described hereinafter.

5 Such pilot valve structure controls the passage of the pressure fluid through tubes 35 and 36 to the diaphragm chambers 18a and 19a of the valves 18 and 19. A hand-operated valve 37 is interposed in the tube 36 so that pressure fluid 10 may be cut off from the diaphragm chamber 19a when it is desired to maintain the valve 18 in a particular position when utilizing the by-pass line 22.

The pilot valve 34 is controlled by a float 38 arranged in chamber 11 in such manner that pressure fluid is applied to the diaphragm chambers 18a and 19a until the float is elevated to an uppermost position, at which time the pilot valve closes and permits pressure to pass from the diaphragm chambers until the float reaches its lowermost position. Obviously as the float descends the liquid is forced out of the chamber 11 by pressure fluid entering through 24, 26 and 21 or through 20 and 22. Of course, if it 25 is unnecessary to force the liquid out, the by-pass pipe 22 may simply serve to equalize pressure in the two tanks 10 and 11.

The three-way pressure control valves 18, 19, may each be of the form shown in Fig. 2. There 30 it will be noted that the valve casing is divided by a partition 39 into an upper chamber 40 and a lower chamber 41, each chamber having a hollow boss 42, 42a, through which a fluid may enter or be discharged. The partition is provided with 35 a port surrounded by a valve seat 43, arranged opposite a second valve seat 44 in a port 45 that communicates with a passageway 46 through which fluid may enter or be discharged. These seats cooperate with a duplex valve head 47 having fluted portions 48 and 49 guided respectively by the ports, and the valve heads are connected to one end of a slideable stem 50 that has its other end secured to a diaphragm 51 arranged in the diaphragm chamber of the valve. A coil 40 spring or the like 52 cooperates with the valve stem to normally hold the valve head in contact with the uppermost valve seat. When fluid pressure is admitted to the compartment 53 of the diaphragm chamber of the valve, the central 45 portion of the diaphragm will move downwardly and cause the valve head to open the upper port and to close the lower one.

It will be understood that so far as the valve 18 is concerned, the portion of the pipe 16 leading 50 from the chamber 10 will be connected to the boss 42; the portion leading to the chamber 11 will be connected to the boss 42a; and the passageway 46 will communicate with the pipe 17. Of course, the tube 35 will be connected to the 55 top of the diaphragm chamber of the valve.

So far as valve 19 is concerned, pipe 20 will be connected with the boss 42; pipe 21, with the boss 42a; branch 26, with the passageway 46; and tube 36, with the diaphragm chamber.

60 It is evident from Fig. 1 that if the valve heads of valve 18 and 19 are closing the upper ports, and oil is being forced from the tank 11 by pressure fluid from an outside source, such fluid will enter through 24, 26 and 21, and the oil will be 65 discharged through pipe 17.

When the float 38 reaches its lowermost position, the pressure fluid will be admitted to the diaphragm chambers of the valves 18 and 19 and cause the valve heads to close the lower ports 70 and open the upper ones. At such time pressures 75

will be equalized in the two tanks by means of pipes 28, 29 and the oil will flow from the chamber 10 through pipe 16 into the tank 11.

The pilot valve 34 may be controlled by the float through the medium of any suitable instrumentalities. One suitable means is illustrated in Figs. 3 and 4.

These views illustrate a pilot valve of the snap action type. It will be noted that the supply of gas under pressure enters a port 58a in 10 the top of a casing 51a and passes to the diaphragms of the diaphragm motor valves 18, 19 by way of a port 52a. The flow is controlled by a valve head 58a mounted on a stem 54 which extends into a housing 55 that is suitably supported on the fluid receiver. The lower end of the valve stem is adjustably connected to a yoke 56 that is pivotally connected to one end portion of a rocking lever 57. The medial portion of the latter is pivotally mounted in the housing on a fulcrum pin 58, and the other end portion of the lever is pivotally connected to a link 59. A cam member 60 has its upper end pivotally connected to the link by means of a pin 61 which also extends through an aperture 62 in the rocking lever. 20 The pin and the wall of the aperture limit the pivotal movement of the link. 25

The cam member 60 is provided with an upper cam surface 63 and a lower cam surface 64, which surfaces cooperate with a roller 65 fulcrumed on 30 a pin 66 supported by a swinging lever 67 which is connected at one end to the float in the fluid receiver and has its other end pivotally mounted at 68 in the housing. A coil spring 69 has one of its ends connected to the housing and its other end connected to the medial portion of the cam member 60 above the cam surfaces.

From the above it will be clear that as the float rises the roller will pass the lower cam surface of the member 60 and in rolling on the upper 40 cam surface it will pull the member 60 down so as to swing the rocking lever into position to open the valve 53a. Of course, the spring during such movement will act to snap the parts into the new positions. When the valve 53a is opened, 45 the gas under pressure will act on the diaphragms of the diaphragm motor valves to shift them so that the pressure gas will flow into the fluid receiver and discharge the contents of the receiver. As the liquid is discharged the float will descend 50 until the roller of the swinging lever reaches the lower cam surface of the member 60 and at such time the spring will function to cause the member 60 to snap upwardly and to close the valve 55 53a.

For the purpose of measuring or metering, I arrange a conventional counter 70 on the line 35 and the counter is provided with an actuating member (not shown) which in turn is moved by the admission of pressure fluid through valve 60 53a each time the head of valve 18 is depressed by its diaphragm.

In operating my improved apparatus, I found that when the oil is prevented from discharging 65 from the chamber 10 while oil is being discharged from chamber 11, a gas lock tends to develop and retard the movement of the oil from chamber 10 to chamber 11 during a subsequent cycle. This affects the capacity of the vessel materially. To overcome the difficulty, a tube 16a places the upper end of chamber 11 in communication with the pipe 16. A hand-operated needle valve 16b and a check valve 16c are interposed in the tube. 70 By using this line, the check valve opens im- 75

mediately, when valve 18 is placed in position for oil to travel from chamber 10 to chamber 11.

From the foregoing, it will be understood that the apparatus may be employed simply for measuring the oil discharged from tank 10 or may be employed for forcing the oil out of the chamber 11 to a higher elevation either with or without measuring the same. If valves 27 and 37 are closed, and valve 23 opened, the apparatus may 10 serve simply to measure the oil from the separator, and at such time the pressure fluid for actuating the valve 18 may be received from an outside source through the pipe 24 or from an inside source through the pipe 25. Of course, if the 15 valve 31 is closed and the valve 29 properly set, gas under pressure from the top portion of the separator chamber 10 will serve to operate the valve 18 when the pilot valve 53a is opened.

This apparatus can function as an ordinary 20 separator, and when the chamber 11 has been filled from chamber 10, the amount of liquid on each discharge of chamber 11 can be measured. During such discharge, as oil cannot enter the 25 chamber 11 from chamber 10, it simply builds up in the chamber 10. Consequently, I can use my improved combination as a separator and also measure each discharge from the lower chamber 11.

I wish it distinctly understood that my improved liquid transferring apparatus as described and illustrated is in the form which I desire to construct it and that changes and variations may be made as may be convenient or desirable without departing from the salient 30 features of the invention, and I therefore intend the following claims to cover such modifications as naturally fall within the lines of the invention.

What I claim and desire to secure by Letters 40 Patent is:

1. In an oil and gas separator of the type having a chamber, a tank, and means for conveying oil from the separator chamber to the tank and from the tank to a point of storage, the improvement which comprises a pressure fluid controlled valve interposed in the said means for controlling the passage of oil from the separator chamber to the tank and from the tank to storage, conduit means placing the upper portion 45 of the tank in communication with the upper portion of the separator chamber, a valve interposed in the conduit means, and means controlled of liquid levels in the tank for controlling said pressure fluid operated valve.

2. In an oil and gas separator of the type having a chamber, a tank, and means for conveying oil from the separator chamber to the tank and from the tank to a point of storage, the improvement which comprises a pressure fluid controlled valve interposed in the said means for controlling the passage of oil from the separator chamber to the tank and from the tank to storage, conduit means placing the upper portion of the tank in communication with the upper portion 50 of the separator chamber, a valve interposed in the conduit means and adapted to be controlled by the operator, and means controlled by liquid levels in the tank for controlling said pressure fluid operated valve.

3. In an oil and gas separator of the type having a chamber, a tank, and means for conveying oil from the separator chamber to the tank and from the tank to a point of storage, the improvement which comprises a pressure fluid controlled valve interposed in the said means for 55

controlling the passage of oil from the separator chamber to the tank and from the tank to storage, conduit means placing the upper portion of the tank in communication with the upper portion of the separator chamber, a second pressure fluid controlled valve interposed in the conduit means, and means controlled by liquid levels in the tank for controlling said pressure fluid operated valves. 5

4. In an oil and gas separator of the type having a chamber, a tank, and means for conveying oil from the separator chamber to the tank and from the tank to a point of storage, the improvement which comprises a pressure fluid controlled valve interposed in the said means for 10 controlling the passage of oil from the separator chamber to the tank and from the tank to storage, conduit means placing the upper portion of the tank in communication with the upper portion of the separator chamber, a second 15 pressure fluid controlled valve interposed in the conduit means, and means controlled by liquid levels in the tank for simultaneously applying pressure to the pressure fluid operated valves to open communication in the conduit means and 20 oil conveying means between the separator and tank, and to close communication between the tank and storage. 25

5. In an oil and gas separator of the type having a chamber, a tank, and means for conveying oil from the separator chamber to the tank and from the tank to a point of storage, the improvement which comprises a pressure fluid controlled valve interposed in the said means for 30 controlling the passage of oil from the separator chamber to the tank and from the tank to storage, conduit means placing the upper portion of the tank in communication with the upper portion of the separator chamber, a second 35 pressure fluid controlled valve interposed in the conduit means, a pipe controlled by the last-mentioned valve for leading a pressure fluid into the conduit means, and means controlled by liquid levels in the tank for simultaneously applying fluid pressure to both of said valves to open 40 communication between the separator chamber and tank through the conduit means and oil conveying means, for closing communication between the pipe and conduit means, and for closing communication between the tank and stor- 45 age. 50

6. In an oil and gas separator of the type having a chamber, a tank, and means for conveying oil from the separator chamber to the tank and from the tank to a point of storage, the improvement which comprises a pressure fluid controlled valve interposed in the said means for 55 controlling the passage of oil from the separator chamber to the tank and from the tank to storage, conduit means placing the upper portion of the tank in communication with the upper portion of the separator chamber and means controlled by liquid levels in the tank for leading gas to the pressure fluid controlled valve for actuating the latter to open communication between the chamber and tank through the oil conveying means and to close communication between the tank and storage. 60 65

7. In an oil and gas separator of the type having a chamber, a tank, and means for conveying oil from the separator chamber to the tank and from the tank to a point of storage, the improvement which comprises a pressure fluid controlled valve interposed in the said means for controlling 70 the passage of oil from the separator chamber to 75

- the tank and from the tank to storage, conduit means placing the upper portion of the tank in communication with the upper portion of the separator chamber, a valve interposed in the conduit means, and means controlled by liquid level in the tank for leading a pressure fluid from an external source to the pressure fluid controlled valve for placing the chamber in communication with the tank and closing communication between the tank and storage.
8. In an oil and gas separator of the type having a chamber, a tank, and means for conveying oil from the separator chamber to the tank and from the tank to a point of storage, the improvement which comprises a pressure fluid controlled valve interposed in the said means for controlling the passage of oil from the separator chamber to the tank and from the tank to storage, conduit means placing the upper portion of the tank in communication with the upper portion of the separator chamber, a second pressure fluid controlled valve interposed in the conduit means, a pilot valve, a valved pipe connected with the pilot valve for leading a pressure fluid to the latter, tubing having an interposed manually operated valve, for leading the pressure fluid from the pilot valve to the pressure fluid controlled valves, and means controlled by liquid levels in the tank for controlling said pressure fluid operated valves.
9. In an oil and gas separator of the type having a chamber, a tank, and means for conveying oil from the separator chamber to the tank and from the tank to a point of storage, the improvement which comprises a valve interposed in the said means for controlling the passage of oil

from the separator chamber to the tank, conduit means placing the upper portion of the tank in communication with said means at a point between the valve, and the separator chamber, a check valve interposed in the conduit means, and means controlled by liquid levels in the tank for controlling the first-mentioned valve.

10. In an oil and gas separator of the type having a chamber, a tank, and means for conveying oil from the separator chamber to the tank and from the tank to a point of storage, the improvement which comprises valve means interposed in said conveying means for controlling the passage of oil from the separator chamber to the tank and from the tank to storage, a conduit placing the upper portion of the tank in communication with the upper portion of the separator chamber, a valve interposed in the conduit means, and means controlled by liquid levels in the tank for controlling said valve means.

11. In an oil and gas separator of the type having a chamber, a tank, and means for conveying oil from the separator chamber to the tank and from the tank to a point of storage, the improvement which comprises valve means interposed in said conveying means for controlling the passage of oil from the separator chamber to the tank and from the tank to storage, a conduit placing the upper portion of the tank in communication with the upper portion of the separating chamber, a valve interposed in said conduit, and means controlled by liquid levels in the tank for simultaneously actuating said valve means and valve.

ROY S. McKEEVER. 35
